Primary Examiner — Cynthia Ramirez*Assistant Examiner* — Michael A Maharajh(74) *Attorney, Agent, or Firm* — Banner & Witcoff, Ltd.(57) **CLAIM**

The ornamental design for an implement for exercise rack, as shown and described.

DESCRIPTION

FIG. 1 is a top, front, left perspective view of an implement for exercise rack showing our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, front, right perspective view thereof.

The broken lines in the drawings are for the purpose of illustrating environmental structure, which forms no part of the claimed design.

1 Claim, 6 Drawing Sheets
